The ornamental design for a lighted flying disk, as shown.

DESCRIPTION

FIG. 1 is a perspective view of the lighted flying disk of my new design;

FIG. 2 is a front elevational view of the lighted flying disk of my new design; it being understood that the rear elevational view, left side elevational view and right side elevational view are identical thereto;

FIG. 3 is a bottom plan view of the lighted flying disk of my new design; and,

FIG. 4 is a top plan view of the lighted flying disk of my new design.
